ABSTRACT: Apparatus for sizing odd length articles such as rods, pipe and the like. A reciprocating conveyor deck having a jogging plate at one end of the deck, forming a barrier to article movement along the deck, forms the sizing apparatus. The conveyor deck includes parallel sidewalls having an article supporting deck extending therebetween in which at least one open area is provided at a designated cut off station. A bundle of rods or other articles to be sized, is loaded onto the conveyor deck. The ties for the bundle are then cut and the conveyor deck is reciprocably driven, to spread the articles along the deck and move the articles into engagement with the jogging plate. The short ends of the articles are then cut off equal distances from the jogging plate at the cutoff station and are allowed to drop to a carry off conveyor.

APPARATUS FOR SIZING ELONGATED ARTICLES

SUMMARY OF THE INVENTION AND OBJECTS

A principal object of the present invention is to provide a new and improved apparatus enabling odd length articles to be sized to uniform lengths, and arranged with a view toward utmost simplicity in construction and efficiency in operation.

Another object of the invention is to simplify the sizing of articles, by utilizing a reciprocating conveyor deck to jog the articles against a jogging surface and align the articles along the jogging surface and then cut the articles to length while on the conveyor deck after stopping operation of the conveyor.

A still further object of the invention is to provide a simple and novel apparatus for sizing odd length articles, in the form of a shaker conveyor deck driven with a shaker conveyor action and having a jogging plate at one end of the deck and an open cutoff station adjacent the opposite end of the deck, in which the articles are moved into engagement with the jogging plate and the short ends of the articles are cutoff at the open bottom cutoff station.

These and other objects of the invention will appear from time to time as this specification proceeds and with reference to the accompanying drawings.

DESCRIPTION OF THE DRAWINGS

FIG. 1 is a top plan view of an article sizing apparatus constructed in accordance with the principles of the present invention.

FIG. 2 is an enlarged fragmentary sectional view taken substantially along line 2-2 of FIG. 1; and

FIG. 3 is a transverse sectional view taken substantially along line 3-3 of FIG. 1, and drawn to the same scale as FIG. 2.

DESCRIPTION OF PREFERRED EMBODIMENT OF INVENTION

In FIG. 1 of the drawings, I have shown an elongated reciprocating conveyor 10, supported above the ground on rollers 11, 11, for reciprocable movement in a straight line path.

The conveyor 10 is shown as being in the form of an open framework, although it need not be open for its entire length, but may be open at a cutoff station designated by a dashed line and indicated by reference character A, to accommodate the ends of rods or bars 12 on the conveyor to be cutoff and dropped through the open portion of the deck at the cutoff station A into a hopper 13 beneath the conveyor, and diagrammatically indicated by dashed lines. The hopper 13 may have communication with a suitable conveyor or of itself may be part of a conveyor.

The conveyor 10 is shown in FIG. 1 of the drawings as being an open spaced from parallel beams in the form of channels 15, the flanges of which face toward the outside. Plates secured the outer ends of the flanges of the channels 15 and are welded or otherwise secured thereto to close said channels and form generally boxlike beams extending for the length of the conveyor. The beams or channels 15 are connected together at the drive end of the conveyor by a beam 17 welded or otherwise secured to the beams 15, 15 and extending thereacross. The beam 17 has a connector or drive plate 19 secured thereto and extending rearwardly therefrom, and forming a drive connector for reciprocably driving the conveyor 10, by a reciprocable conveyor drive mechanism 20, of a conventional form. The opposite or outby end of the conveyor 10 has an upwardly facing channel 21 extending thereacross and welded or otherwise secured to the channels 15, 15. A stiffening bar 22 is welded or otherwise secured to the web of the channel 21 between the flanges thereof and extends between the beams 15, to stiffen said channel and channel and accommodate said channel to limit travel of the articles 12 and bring the articles into alignment with each other at their forward ends. A buffer or fogging plate 23 extends across the web of the channel 21 in the plane of travel of

the articles 12 along said channel and faces the ends of the articles and is abutted thereby to form a jogging surface to jog the articles into alignment with each other. The jogging plate 23 is shown as being made from a plastic material. A polyurethane plastic material has been found to be a desirable material to be abutted by the articles moved along the conveyor by the conveying action thereof and to reduce rebound to a minimum. Various other materials having some resiliency and acting as buffers may also be used.

10 The material carrying surface of the conveyor 10 is formed by a plurality of parallel spaced cross tubes 25, spaced along the conveyor between the webs of the beams 15 and welded or otherwise secured thereto. Reinforcing plates in the general form of gusses 26 are welded to opposite sides of the tubes 25 and extend angularly outwardly therefrom toward the webs of the channels 15 and are welded or otherwise secured thereto. The top surfaces of the tubes 25 thus form a material carrying surface for the articles to be sized, to convey said articles along the conveyor deck as the conveyor is reciprocably driven.

15 The rollers 11, supporting the conveyor are rotatably mounted on and extend inwardly of roller brackets 27, which are mounted on the tops of posts 29 spaced along the conveyor. The posts 29 may extend upwardly of a frame structure imbedded in the foundation (not shown) for the sizing apparatus to form a solid support for the reciprocating conveyor 10.

20 The shaker conveyor drive mechanism 20 is of a conventional form, and as shown in FIG. 1 of the drawings, includes a pair of parallel rocker arms 30 extending upwardly of opposite ends of an oscillatably driven shaker conveyor drive shaft 31, and having drive links 32 pivotally connected thereto. The drive links 32 have driving engagement with a drive yoke 33 25 extending under the drive plate 19 and connected thereto as by a vertical pivot pin 35. The shaker conveyor drive mechanism is no part of the present invention except insofar as it provides the means for reciprocably driving the conveyor, back and forth with a shaker conveyor action, to progress articles deposited the reon from the inby to the outby end of the conveyor trough into engagement with the jogging plate 23.

30 In operation of the apparatus, a bundle of articles of random lengths, such as rods or pipe is placed on the deck of the conveyor formed by the spaced transverse tubes 25, 25. The straps of the bundle are then cut to accommodate the articles to spread out along the open deck of the conveyor. The conveyor drive mechanism 20 is then started to reciprocably drive the conveyor with a shaker conveyor action, and advance the articles into engagement with the jogging plate 23. When all of the articles are in engagement with jogging plate 23, the shaker conveyor drive mechanism is stopped. A flame cutter or other cutting device may then burn off the pieces over a predetermined length at the cutoff station A. The random ends may then drop into the hopper 13, to be carried away as scrap. The sized articles are then bundled on the conveyor deck and removed to be transported to a source of use.

35 It should be understood that the articles to be sized are relatively long and may be 40 feet long and longer, although they need not necessarily be this long. 40 foot lengths are standard lengths for many rods and pipes, and where the articles may be of random lengths, it is required that all of the articles be cut to the same length.

40 While I have herein shown and described one form in which the invention may be embodied, it should be understood that various modifications and variations in the invention may be attained without departing from the spirit and scope of the novel concepts thereof.

45 I claim:

50 1. In an apparatus for sizing elongated articles; an elongated conveyor deck having an upstanding jogging plate forming; a barrier to article movement along the deck; means including a reciprocatory drive unit having connection with the conveyor deck and arranged to impart a

straight line reciprocable motion to the conveyor deck, to move articles placed on the deck into aligned engagement with the jogging plate; and a cutoff station adjacent the opposite end of said deck from said jogging plate.

2. The structure of claim 1, wherein the elongated conveyor deck comprises a pair of sidewalls having an article supporting deck disposed therebetween in which the means providing a cutoff station includes at least one open area in said deck, accommodating the random ends of the articles cut to size to drop through said open area for removal. 10

3. The structure of claim 1, wherein carryoff means is provided below said cutoff station for receiving the random ends of the articles dropping through said open area, and carrying the random ends of the articles away from the sizing apparatus. 15

4. An apparatus for sizing elongated articles comprising: an elongated conveyor deck supported for reciprocable movement and having an inby end and an outby end; an upstanding jogging plate extending across the outby end of said conveyor deck and forming a barrier to article movement along said deck; said elongated conveyor deck also having an open portion forming a cutoff station; and a shaker conveyor drive unit having driving connection with said conveyor deck arranged to impart a reciprocable shaker conveyor motion to said conveyor deck to move articles placed on said deck toward said jogging plate to engage said jogging plate and be moved into aligned rela- 20

tion thereby. 5. An article sizing apparatus in accordance with claim 4, wherein the jogging plate is a resilient buffer plate extending across said conveyor deck in the line of travel of the articles along said conveyor deck, to buff the travel of articles along said deck and prevent rebound of the articles upon engagement with said buffer plate. 5

6. An article sizing apparatus in accordance with claim 4: wherein the conveyor deck comprises a pair of side frame members and end frame members connecting said side frame members together; wherein spaced cross members parallel to said end frame members space said side frame members apart and have material supporting surfaces disposed beneath the level of side frame members; wherein the jogging plate extends across an end frame member and is backed up thereby; and wherein at least one of the spaces between said cross members forms a cutoff station and accommodates the cutoff random ends of the articles to drop through the open space between said cross members. 15

7. An article sizing apparatus in accordance with claim 6, wherein the jogging plate is made from a resilient plastic material to absorb the shocks of the articles engaging said buffer plate and to prevent rebound thereof. 25

8. An article sizing apparatus in accordance with claim 7, wherein the buffer plate is made from polyurethane. 20

UNITED STATES PATENT OFFICE
CERTIFICATE OF CORRECTION

Patent No. 3,549,137

Dated December 22, 1970

Inventor(s) Edward J. Berk

It is certified that error appears in the above-identified patent and that said Letters Patent are hereby corrected as shown below:

Column 1, line 54, change "spaced" to --framework formed--.

Column 1, line 56, change "secured" to --16 abut--.

Column 1, lines 71 and 72, delete "and channel".

Column 1, line 74, change "fogging" to --jogging--.

Column 2, line 40, change "the reon" to --thereon--.

Signed and sealed this 30th day of March 1971.
